UNITED STATES PATENT OFFICE.

CALVIN G. UDELL, OF INDIANAPOLIS, INDIANA.

IRONING-TABLE.

SPECIFICATION forming part of Letters Patent No. 340,641, dated April 27, 1886.

Application filed June 2, 1884. Serial No. 133,513. (No model.)

To all whom it may concern:

Be it known that I, CALVIN G. UDELL, a resident of Indianapolis, Marion county, Indiana, have made certain new and useful Improvements in Ironing-Tables, a description of which is set forth in the following specification, reference being made to the accompanying drawings, in the several figures of which like letters indicate like parts.

10 My improvement relates to the construction of tables having a removable top and folding frame-work, and is adapted to be used as a table for ironing, and other purposes where a folding table is desired, and will be understood from the following description.

15 In the drawings, Figure 1 represents a side view of an ironing-table embodying my device. Fig. 2 is an end view of the same; Fig. 3, a view with the top removed and the frame-work folded down upon the cross-bar. Fig. 4 is a longitudinal section through the hinges and end of the cross-bar enlarged. Fig. 5 is a side view of one of the hinge-plates.

20 In detail *st* are the ends or standards of the frame, constructed in the manner shown in Fig. 2, of an upright, a foot, and a top cross-piece, to one of the latter of which are fastened by screws small iron clamps *c*, and on the other cross-piece a strip of rubber, *r*, is fastened, the 25 top *t*, which may be made in any convenient shape, being clamped down at one end upon the frame-work by the clamps *c* and resting at the other upon the rubber strip, which prevents it from slipping. The clamps and rubber are only used when an ironing-table is intended, and an ordinary table-top may be put upon the same frame-work, a very simple mechanical change only being required to adapt 30 any form of top to the frame-work.

35 *h* represent hinge-plates, which are secured by screws to each side of the standards *st*, and at the rear end these plates are provided with projections *b*, which enter sockets formed in each side of the cross-bar *cb*, as 40 shown in Fig. 4, thus forming a hinge, by means of which the standards may be folded down upon the cross-bar. The outer ends of 45 these hinge-plates are provided with flanges, which together nearly inclose the outside of

the standard, and the flanges *sp*, integral with the plates, are for clamping the wood of the standard on the inside, thus making all very secure.

sb are iron braces, slotted nearly their entire length, and pivoted at their upper ends to the standards at *l*. Their lower ends are turned up at a right angle to the main portion of the brace, the slot also extending up at a similar right angle, and then secured by a screw, *s*, fastened to the cross-bar. The angle in the slotted brace and in the slot allows the brace, when drawn out to its full extent by the opening of the frame, to be pushed down, so that the stop *s* is thus made to abut against the side of the slot and lock it firmly in its position, and until the brace is pulled up the table cannot be folded down, as the brace cannot slide on the stop *s* until it enters the long part of the slot.

The clamp *c* has its lower end pivoted to the head of the standard *st*, as shown in Fig. 2, and its upper end, which is formed in the shape of a flat hook, is brought over the end of the top *t*, the end of which top abuts against the shank of the clamp, as shown in Fig. 1.

What I claim, and desire to secure by Letters Patent, is the following:

1. An ironing-table composed of upright standards *st*, connected by the cross-bar *cb*, hinged to the central portion of the standards by the hinges *h*, the slotted braces *sb*, pivoted to the standards above such cross-bar and provided with right-angled slots at the opposite end, which move upon the stops *s*, secured to the cross-bar *cb*, the removable top *t*, the clamp *c*, and the rubber friction-strip *r*, all combined substantially as described.

2. An ironing-table composed of a folding frame supporting a removable top, one end of which is held in place by a suitable clamp and the other resting upon a rubber friction-strip connected with the other standard, substantially as described.

Witness my hand this 31st day of May, 1884.

CALVIN G. UDELL.

Witnesses:
